His Attorney

UNITED STATES PATENT OFFICE.

LEONARD H. DE FERNELMONT, OF PHILADELPHIA, PENNSYLVANIA.

BUILDING TILE AND WALL MADE THEREFROM.

1,409,284.

Specification of Letters Patent. Patented Mar. 14, 1922.

Original application filed May 8, 1918, Serial No. 233,218. Divided and this application filed April 30, 1919. Serial No. 293,599.

To all whom it may concern:

Be it known that I, LEONARD H. DE FERNELMONT, a citizen of the United States, and resident of Philadelphia, county of Philadelphia, and State of Pennsylvania, have invented an Improvement in Building Tiles and Walls Made Therefrom, of which the following is a specification.

My invention has for its object the construction of a special form of building tile particularly useful for inside walls, as partitions, and in which the tile will properly interlock with other tiles of the same character and provide ventilating apertures 15 through the wall formed of such tiles.

My object is also to so form the edges of the abutting walls of the tiles that they may be placed together without cement so as to come into accurate alignment and 20 thereafter have their jointed portions sealed with suitable cement, whereby the walls may be quickly erected and at a much lower cost than is possible where the abutting edges of the tiles are directly laid in cement, 25 as has heretofore been customary practice.

This application is a division of my application Serial No. 233,218, and filed May 8, 1918, which describes both the mould for making the tile and the construction of the 30 tile, this application being restricted to the tile itself and the use thereof in the formation of the wall structure.

My invention consists of a rectangular flat tile having two of its adjacent edges 35 provided with projecting ribs and the remaining two adjacent edges provided with correspondingly shaped grooves whereby a plurality of tiles may be interlocked by the ribs of any tile engaging the grooves in the 40 next adjacent tiles, and said tiles further having opposing edges between the ribs and grooves on the one part and the outside walls or faces on the other part, said abutting edges being beveled so that when two 45 tiles are interlocked they provide between them open grooves, preferably of a V-shape cross section, which receives the sealing cement for smoothing the outer surface of the wall and making a sound-tight joint between the abutting tile.

My invention also comprehends the method of erecting a wall composed of a plurality of tiles which have interlocking engaging edges to bring the several 55 tiles into accurate engagement and present

grooves in the faces between the tile along the line of juncture and thereafter sealing the joints of the tile by introducing cement into the grooves to form a smooth outer surface. 60

My invention will be better understood by reference to the drawings in which:

Figure 1 is a perspective view of a building tile embodying my invention;

Figure 2 is an elevation of my improved 65 building tile with a portion of the same broken away to show the interior;

Figure 3 is a vertical cross section through a wall composed of a plurality of my improved building tile united in interlocked 70 arrangement; and

Figure 4 is an edge view of the tile.

The body 1 of the tile is rectangular in shape and with flat parallel walls or faces. On two of its edges at right angles, the tile 75 is provided with raised ribs 3 which in cross section are tapered so that the outer edge of the rib structure is of less width than the width of the projection at its base. Similarly, the other two right angled edges of 80 the tile are provided with grooves 3^a which in cross section correspond to the cross section of the raised ribs 3, said grooves being formed with inclined side walls and with a narrower bottom than the width of 85 the opening at the top. The shape of the grooves 3^a are the inverse of the shape of the ribs 3, so that a rib of one tile may snugly fit into the groove of the adjacent tile; and said ribs and grooves provide an 90 interlocking connection between the tiles, which hold them in accurate alignment in the same plane. The maximum width of the ribs 3 and grooves 3^a is considerably less than the total thickness of the tile, so that 95 there is provided between the said ribs 3 and the outer faces of the tile, beveled surfaces 4, and similarly between the grooves 3^a and the outer surface of the tile are arranged beveled surfaces 5. The bevel of the 100 opposite edges 4 and 5 have their incline so that said surface, if continued, would intersect, and the result of this construction is that when the tiles are arranged one upon the other, as indicated in Figure 3, the beveled edges 4 and 5 of adjacent tiles provide recesses 6 which are preferably V-shaped, and so that the bounding edges of the face of the abutting tiles both below and on the lateral sides are separated by these V-shaped 110

grooves 6. This construction provides the channels or grooves between the tiles for receiving cement as indicated at 8, and which thereby seals the joints and also strengthens 5 the interlocked connection between the tiles and holds them in perfect alignment. Furthermore, the fact that the bounding edges of the surfaces of the tiles are not permitted to come into direct contact, avoids the tendency to chipping the edges which invariably takes place where the edges abut solidly one upon the other, as has heretofore been the practice.

In the present construction, the tiles are 15 interlocked by positive connection through the ribs and grooves and without any necessity for cement, and thereafter the grooves 6 are cemented in the manner above described. The result of this construction, 20 aside from making an excellent wall, enables one man to accomplish a great deal of more work measured in square feet of wall surface than is possible in those constructions heretofore employed in which the successive tiles are required to be united through 25 joints of cement or mortar. In the method of construction here shown, the workman may erect several times more wall structure than he could accomplish in those forms 30 where the cement was required to be introduced between the tiles when setting them in place, and consequently the cost of erecting a wall of this nature is greatly less than similar walls under the old construction have 35 cost for erection. It is also manifest that a neater and cleaner job may be accomplished by employing the tile of the present invention than those forms in which the joints were laid in cement or mortar. It is also 40 to be understood that in erecting a wall having my present improvement, the accuracy in positioning the tile is absolutely assured, because the tiles are all molded exactly alike and when interlocked are bound to take definite positions, whereas when tiles are set in 45 cement or mortar, it is not easy for the mason to properly position every tile in respect to the adjacent tiles, as they are liable to come a little too high or a little too low or 50 not in true vertical alignment, due to the irregularity in the amount of cement or mortar between the tiles.

As shown in the drawings, the tile is provided with a plurality of vertical apertures 55 2 which are preferably tapered as shown, the ends of the apertures opening at their largest ends in the recessed or grooved portion 3^a, and having their smaller ends opening through the rib portion 3, as shown. The 60 smaller end of these apertures 2 are choked down by a shouldered portion through which a relatively small aperture 7 is provided and which opens through the central portion of the rib 3. In this manner the tile is made 65 light and withal, strong. Furthermore,

these vertical apertures of one tile are brought into alignment with the similar apertures in the tiles above and below so that, as indicated in Figure 3, when a plurality of tiles are erected to constitute the 70 wall, there are continuous ventilating passages vertically through the walls and which provide dryness; and at the same time the choking of these passages at the points 7 make said passages bad conductors of sound, 75 which always results when the continuity of the sound passages are interrupted by contractions. The construction of my improved tile insures an excellent, light and dry wall, 80 which is effective as a non-conductor of sound from one room to the next, and consequently walls of this character are desirable between apartments and offices.

I do not restrict myself to any particular character of plaster material from which to 85 mold the tiles, as any suitable material heretofore in use may be employed, but the improved tile shall have its edges partly grooved and partly ribbed with flaring or inclined shoulders at each side of the grooves 90 and ribs, and further provided with a plurality of parallel tapered apertures having shouldered and contracted passages at one end where they extend into one of the ribbed edges. 95

It will now be apparent that I have devised a novel and useful construction which embodies the features of advantage enumerated as desirable, and while I have in the present instance shown and described the 100 preferred embodiment thereof which has been found in practice to give satisfactory and reliable results, it is to be understood that I do not restrict myself to the details, as the same are susceptible of modification 105 in various particulars without departing from the spirit or scope of the invention.

Having now described my invention, which I claim as new and desire to secure by Letters Patent, is:—

1. A tile consisting of a rectangular body portion having two of its adjacent edges formed with deep grooves and the remaining two edges formed with corresponding ribs, said ribs of less width than the thickness of the tile and provided with oblique side walls and bounded on each side with longitudinal surfaces extending from the base of said ribs to the outer respective faces of the tile, said surfaces arranged obliquely 115 and with a lesser incline than that of the sides of the rib forming an obtuse angle between the said walls of the rib and the oblique bounding surfaces, and the groove of the remaining edges of the tile having inclined side walls and bounded on opposite sides by oblique surfaces extending between the said groove and the respective faces of the tile and in which further the oblique 120 faces of the grooves form with the oblique 125 faces of the grooves

bounding surfaces acute angles and also forming relatively sharp corners along the grooves adapted to tightly fit upon the ribs of adjacent tiles whereby when such tiles are assembled one upon the other to form a wall, V-shaped grooves opening outward are provided on each side adjacent to their abutting edges for reception of cement, and in which further the oblique bounding surfaces both on the ribbed and grooved edges meet the outer faces of the tile in obtuse angular edges whereby all sharp corners in exposed position are eliminated.

2. A tile consisting of a rectangular mold-ed body of uniform thickness having two of the adjoining edges thereof formed with deep grooves and the remaining edges formed with corresponding ribs, and said body further provided with bounding surfaces on the opposite sides of the grooves and ribs respectively said surfaces inclined outwardly and terminating in the respective outer parallel wall surfaces and forming with them obtuse angular edges to provide a lesser area on the outer exposed vertical side surfaces than the vertical sectional area adjacent the said grooves and ribs, whereby abutting interengaging tiles provide outwardly flaring open V-grooves for reception of cement.

3. A wall composed of a plurality of tiles directly interlocked both in a vertical direc-

tion by immediate contact and in a lateral direction by means of ribbed and grooved interengaging parts on the respective adjacent edges of the abutting tiles, and in which further the adjacent edges on each side of the interlocking portions of abutting tiles are provided with grooves, said grooves being outwardly flaring and opening on the faces of the wall and between the abutting tiles, and cement filling the said grooves to form a sealed joint between the tiles and a smooth outer continuous surface in the plane of the tiles and acting to hold the tiles against tilting out of their common plane of alinement.

4. The invention according to claim 1, wherein a number of tiles of the character therein stated are assembled edge to edge both vertically and laterally and fitted as therein stated to provide a series of intersecting V shaped grooves outwardly flared on both sides of the wall, said V shaped grooves filled with cement having the exposed surfaces smoothed to the same plane as the outer surfaces of the tiles and of triangular cross section, said cement forming a sealed joint between the tiles and acting to hold the tiles against tilting out of their common plane of alinement.

In testimony of which invention, I hereunto set my hand.

LEONARD H. DE FERNELMONT.
